US00D525871S

(12) **United States Design Patent** (10) **Patent No.:** **US D525,871 S**
(45) **Date of Patent:** **** Aug. 1, 2006**

(54) **SPRAY DISPENSER**

(75) Inventors: **Mark A. Zeh**, Munich (DE); **Shilajeet Banerjee**, Belmont, CA (US); **Markus Diebel**, San Francisco, CA (US); **Nancy J. Serpillo**, Menlo Park, CA (US)

(73) Assignee: **Warner-Lambert Company, LLC**, Morris Plains, NJ (US)

(**) Term: **14 Years**

(21) Appl. No.: **29/211,386**

(22) Filed: **Aug. 16, 2004**

(51) **LOC (8) Cl. 09-01**

(52) **U.S. Cl. D9/521; D9/551; D9/558**

(58) **Field of Classification Search** D9/414, D9/435, 443, 445, 448, 516, 521, 529, 530, D9/535, 549, 551, 553, 558, 566, 572-573, D9/682, 686-694; D28/7, 76, 91.1; D23/366; D3/215; 222/321.1-321.9; 215/382-384, 215/396, 398; D24/110

See application file for complete search history.

Primary Examiner—Carol Rademaker

(74) *Attorney, Agent, or Firm*—Evan J. Federman; Darryl C. Little; Karen G. Horowitz

(57) **CLAIM**

We claim the ornamental design for a spray dispenser, as shown and described.

DESCRIPTION

FIG. 1 is a front perspective view of the spray dispenser; FIG. 2 is a front elevational view of the spray dispenser; FIG. 3 is a top plan view of the spray dispenser; FIG. 4 is a bottom plan view of the spray dispenser; FIG. 5 is a right side elevational view of the spray dispenser, the left side elevational view being a mirror image; and, FIG. 6 is a rear elevational view of the spray dispenser. The broken lines in the drawings are for illustrative purposes only and form no part of the claimed design.
